US0D1061955S

(12) **United States Design Patent** (10) Patent No.: **US D1,061,955 S**
(45) Date of Patent: ** Feb. 11, 2025

(54) **TESSELLATING BOARD**

(71) Applicant: **Elmdene Group, Ltd.**, Coventry (GB)

(72) Inventors: **James Edward Douglass**, Coventry (GB); **Russell Porter**, Coventry (GB); **Stefan Holmes**, Coventry (GB)

(73) Assignee: **Elmdene Group, Ltd.** (GB)

(**) Term: **15 Years**

(21) Appl. No.: **29/851,784**

(22) Filed: **Aug. 31, 2022**

(30) **Foreign Application Priority Data**

May 17, 2022 (GB) 6208534

(51) **LOC (15) Cl.** **25-01**

(52) **U.S. Cl.**

USPC **D25/158**; D25/138; D25/157

(58) **Field of Classification Search**

USPC D5/15, 56, 60-62; D25/138, 157, 158, D25/164, 199

CPC E04C 2002/008; E04C 2/04; B32B 5/16; B32B 2607/00

See application file for complete search history.

(57) **CLAIM**

The ornamental design for a tessellating board as shown and described.

DESCRIPTION

FIG. 1 is a front view of a tessellating board of the present general inventive concept;

FIG. 2 is a rear view of the tessellating board of FIG. 1;

FIG. 3 is a top view of the tessellating board of FIG. 1;

FIG. 4 is a left side view of the tessellating board of FIG. 1;

FIG. 5 is a right side view of the tessellating board of FIG. 1; and,

FIG. 6 is a bottom view of the tessellating board of FIG. 1.

1 Claim, 1 Drawing Sheet
